United States Patent Office.

WILLIAM BURNET, OF NEW YORK, N. Y.

Letters Patent No. 66,213, dated July 2, 1867.

IMPROVEMENT IN TOPS FOR MUCILAGE AND VARNISH-BOTTLES.

The Schedule referred to in these Letters Patent and making part of the same.

TO ALL WHOM IT MAY CONCERN:

Be it known that I, WILLIAM BURNET, of the city, county, and State of New York, have invented a new and improved Cap or Cover for Mucilage, Varnish, and other Bottles, where it is desirable to vary the quantity of liquid taken up by the brush; and in order that others skilled may understand the nature of my invention, I give the following full and exact description thereof, illustrated by the accompanying drawings, and referred to in this schedule by the letters and figures marked thereon.

The nature of my invention consists in making a cap or top of rubber or other elastic material, of such a shape that while it covers the bottle from air and dust, still allows of a limited up and downward motion to the brush which passes through its centre to the liquid in the bottle.

These caps, as usually made, are of brass, pewter, or Britannia, and, except my improved cap, patented February 2, 1864, have no provision for varying the quantity of liquid taken up by the brush without too much trouble.

By this flexible cap I gain many advantages over the old patterns, and by the simplest means, as the cap itself furnishes the spring for the up and down motion to vary the quantity of liquid at any time, and also the spring to clasp the handle of the brush in such position that it will always just touch the liquid as it is used up from the bottle; and can thus arrange my brush so that a drop or two of mucilage can be taken out to seal a letter, or by simply pressing the handle down, without altering the position of cap or brush, obtain sufficient to seal one or more newspapers. One great disadvantage of the old form is, that your brush takes up too much mucilage, and on most occasions it is to be wiped off from it on the edge of the bottle, and the mouth of the bottle, brush, and cap soon are so clogged as to render the whole affair useless.

Description of Drawings.

Figure 1 shows the parts in longitudinal vertical section.

A A, the bottle; B B, the elastic cap, which is dome-shaped, of any convenient form, where the handle C passes through a hole in its centre, just large enough to clasp the handle C, so that it will require a little force to move the handle up and down in it. D, the brush, just touching the mucilage F. E is the ferrule, attaching brush and handle together. The dotted lines at the under side of the cap show the shape which it takes by downward pressure of the handle; and the dotted lines at the end of the brush show its immersion in the liquid when so pressed. The cap is made sufficiently thick to spring back to its first position when left to itself.

Figure 2 shows the top and bottle in perspective, the same letters referring to the same parts.

Mode of Operation.

When the bottle is nearly full of the liquid, the brush is to be drawn up so that it will just touch the surface of it. If only a small quantity is to be used, it is only necessary to take it out without downward pressure; if more is needed, then press down the handle, and the yielding nature of the dome of the cap will allow a deeper immersion of the brush in the liquid. As the contents of the bottle are exhausted, push the handle of the brush further down in the cap till it is all used up.

I am aware that elastic tops have been before used, made of rubber, as, for instance, to cover nursing-bottle tubes, &c. Therefore I do not claim broadly a rubber bottle top; but what I do claim, is—

1. An elastic cover for gum and varnish-bottles, so shaped that it will at the same time cover the mouth of the bottle, furnish a spring to allow endwise motion to the brush, and return it to its normal position, and clasp the handle of the brush so that it may be moved up and down in the cap, and held at any desirable height.

2. I claim the combination of the above top, made of any suitable elastic material, with a brush for varnish and mucilage-bottles, all made and operating substantially as described, or their mechanical equivalents.

WILLIAM BURNET.
